UNITED STATES PATENT OFFICE

2,474,765

PACK OPENING AND SHEET RECEIVING
MEANS

Bernard G. Vaughn and William V. Fell, Zanesville, Ohio, assignors to Armco Steel Corporation, a corporation of Ohio

Application August 24, 1945, Serial No. 612,492

6 Claims. (Cl. 271—10)

1

As is well-known in the production of thin gauge sheets on the hot sheet mill, it is the practice after certain roughing passes to match the rolling pieces and roll them together. In the course of further rolling operations, matching is again resorted to one or more times; and it is not infrequent in such rolling operations to end with a "pack" of the desired sheet breadth and thickness, and containing eight or even more individual sheets in superposed position.

Sheets in such packs tend to become tightly stuck together so that the packs have to be "opened." This has hitherto commercially been done by hand. It is the practice to shear off the rough edges of the pack. Then the pack is placed upon a floor and an operator with tongs bends a corner of the pack back and forth so as to effect an initial separation of the sheets at the corner. Wearing heat resisting shoes, the operator grasps a corner of the topmost sheet in his tongs and, holding down the pack with his foot, strips the sheet partially away from the remainder of the pack. By reason of the large size of sheets in ordinary practice, it is not possible fully to strip a pack from one end only. As a consequence, the operator will separate the sheets at the other end of the pack, usually at a diagonally opposite corner, and complete the stripping of the first sheet from that end and in the opposite direction. Other sheets in the pack are successively stripped in the same way.

The operating conditions under which stripping is done are unpleasant, and the work is back breaking. The initial separation of the sheets crumples or wrinkles them for a considerable distance inwardly from the corners, generally at two corners, but frequently at more, since if an operator is unable to produce effective separation at one corner, he will proceed to another. The crinkling or creasing at the corners results in a large scrap loss. Many of the packs have their sheets set or stuck together very strongly, and, particularly with materials of more or less brittle character, such for example as silicon steel, wastage through the tearing of sheets is high. The 45 packs, moreover, have to be separated by a sharp jerking pull on the part of the operator. The sudden application of pull increases the breakage and tearing of brittle materials, and frequently tends to produce bends or creases in more ductile materials, again leading to excessive throw-out.

The fundamental object of our invention is the provision of mechanical means for separating packs, not alone to avoid the undue physical difficulty of hand pack opening, but also to open 55

2

packs with far less wastage and destruction of materials. It may be stated that our pack opener in commercial operation is opening packs of hot rolled silicon steel with a throw-out of less than 1%. The initial operation of effecting sheet separation at a corner results in so much less crinkling or crumpling of the sheets as to involve in itself no wastage, and but one corner of the pack is affected. The separation of sheets from the pack 10 is a continuous and uniform operation involving a steady application of power so that loss from tearing or creasing of the sheets is avoided and, as hereinafter explained, it is usually possible to effect the separation of all sheets in a pack, or 15 of a large number of them, simultaneously. Hence, the operation of pack opening is greatly speeded up with attendant further savings. These accomplishments may be considered as further objects of the invention.

20 Other objects of the invention, which will be set forth hereinafter or will be apparent to one skilled in the art upon reading these specifications, are accomplished, together with the main objects, by that construction and arrangement of 25 parts of which we shall set forth an exemplary embodiment. Reference is made to the drawings wherein:

Figure 1 is a plan view, and Figure 2 an elevation of a leading or first portion of our apparatus 30 in which separation of the sheets at a corner is effected.

Figure 3 is an elevational view of a succeeding apparatus in which actual separation of the sheets occurs.

35 Figure 4 is an elevational view illustrative of the carriage traverse.

Figure 5 is a partial elevational view taken from the opposite side of the carriage.

Figures 6 and 6a are diagrammatic representations of control means.

40 Figure 7 is a wiring diagram for motor control.

Figure 8 is a partial plan view of a catcher apparatus, and Figure 9 is an elevational view thereof with parts in section.

Figure 10 is an end elevational view of a catcher showing a throw-out mechanism.

Figure 11 is an enlarged cross-section of a portion of a catcher illustrating more clearly certain features of the throw-out mechanism.

50 In the practice of our invention, we provide a means which, receiving a pack, clamps it to a bed adjacent one corner, whereupon a power actuated comb or rack device engaging the corner of the pack, subjects the corner beyond the clamp to a rapid series of flexing movements, re-

sulting in sheet separation at the corner. The pack is then released and passes into a second portion of the apparatus, where it is brought to rest upon a bed and held in position by a series of magnetic hold-downs distributed throughout its length in such a way as to retain the position of the pack during the removal of sheets therefrom. Above this bed, there is a carriage including pinch rolls. Means are provided to cause the carriage to move longitudinally of the bed for a distance at least as great as the length of the pack. The pinch rolls are also driven in a timed relationship to the movement of the carriage. When the pack is in position and is held to the bed by means of the magnetic hold-downs, the operator grasps a loosened sheet at the corner with his tongs and, pulling upwardly on it, strips it just sufficiently to enable him to introduce it between the rolls of the pinch roll combination on the carriage. We preferably provide a limit switch to be actuated by the sheet so introduced; this switch starts the traverse of the carriage. The sheet is pulled upwardly and over the lower pinch roll (which has a diameter sufficient to prevent crimping of the sheet), and as this pull is exerted, the carriage moves progressively toward the opposite end of the pack. Thus the sheet is continuously and progressively stripped from the pack, is inverted through the action of the pinch rolls, and is delivered beyond the second section of the apparatus.

When the first sheet has been so stripped and delivered, an automatically acting mechanism returns the carriage to its initial position, ready to receive a second sheet. Thus the sheets may be individually and successively stripped from the pack.

The catcher embodies stacking means hereinafter to be described, and preferably it also embodies a means whereby sheets, which are seen to be imperfect or non-commercial for any reason, may be prevented from going into the stack and delivered instead to an offside position where they may be removed as scrap.

We have also found that it is possible to strip a plurality of sheets from a pack and in many instances all of the sheets in a pack simultaneously. If an operator effects an initial separation of two or more sheets and introduces these sheets into the pinch rolls with their ends in offset relationship, the action of stripping a plurality of the sheets from the pack will result also in a separation of the sheets from each other, as will hereinafter be more fully explained.

Referring to Figures 1 and 2, we have shown, mounted upon a suitable framework 1, a table 2, which may conveniently be in the form of a roller conveyor. This table receives the unopened packs, preferably from a conveyor operating in a transverse direction adjacent the table 2 and serving to deliver the packs from a shear at which the pack edges have been trimmed. The last mentioned conveyor and shear have not been illustrated.

When a pack has been delivered to the table 2, it is brought to rest thereon in such a way that its end overlies a supplementary table 3, mounted on suitable standards 4. Stop 5 is provided to position the end of the pack and a side guide element 6, pivoted on the frame, as at 7, is operated by a pull link 8 in such fashion as to move the pack against a stationary stop means 9 on the frame 4. When the pack is properly positioned, one of its corners extends beyond a diagonally cut-away corner of the table 3, indi-

cated at 3a. A hold-down clamp element 10 is brought against the pack 11 so as to clamp it against the table 3. The clamp 10 is cut away along the same line as the table so that the corner of the pack extends beyond both. The clamp 10 may be actuated in any suitable fashion. We have shown it actuated by the piston 12 of an air cylinder 13 mounted on an overhead frame element 4a on the framework 4. A means 14 for engaging the pack corner is mounted for vertical reciprocation. This means again may be actuated in any way desired. We have shown it connected to the piston 15 of an air cylinder 16 mounted to the floor or to a portion of the frame 4. The engagement means 14 may conveniently be in the form of an angle iron to which transverse members, indicated at 14a in Figure 2, have been welded to form a sort of comb or rack. As the member 14 is driven upwardly or downwardly by the air cylinder 16, the comb teeth 14a subject the corner of the pack to a series of gentle flexing movements which effectively separate the sheets of the pack at the corner without wrinkling or crumpling the metal.

The link 8 for operating the side guide 6 may be connected, if desired, by a suitable lever linkage 17 with the clamp 10 so that as this clamp descends, the side guide positions the pack prior to the actual clamping. The link 8 may, however, be otherwise moved, if desired.

When the sheets have been separated or loosened from each other at the corner of the pack, the clamp 10 is released and the pack is then moved to a second section of the machine. This is usually done by an operator with tongs sliding the pack over the conveyor table 2; but it may be done mechanically by powering the conveyor, as will be readily understood.

In the second section of the machine, as illustrated in Figure 3, we provide on a suitable framework 18, a conveyor table 19. To assist in moving the pack over the conveyor tables 2 and 19, both may be slanted slightly in the direction in which the packs proceed.

A suitable stop means 20 is provided to position the pack 11 on the table 19 and, where the packs to be opened are variable as to size, we make the pack stop means 20 adjustable. In connection with the conveyor table 19, we provide magnetic hold-down means. These may be of various types and styles, but are so constructed or so arranged and assembled as to exert an adequate holding-down action transversely across the pack. One at least of these hold-down means, as shown at 21, will be located near the left-hand end of the pack in Figure 3. Another or others will be located, as at 22, near the other end of the pack. The magnetic hold-downs may be made adjustable along the length of the conveyor table 19, or they may be located in fixed relation and provided in such numbers as to exert an effective retaining action upon the packs of various lengths throughout the extent of these packs.

We prefer magnetic hold-down means for the reason that they do not require members engaging the pack on its upper surface and thus leave the pack free for the stripping operation hereinafter described. With magnetic hold-downs of suitable strength, however, we have not found it necessary to locate them at close intervals throughout the length of the pack. One or more hold-downs near both ends of a pack are usually sufficient.

Above the level of the conveyor table 19 on

suitable trackways 23, we provide a traveling carriage 24 mounted thereon by means of rollers 25. A pair of pinch rolls 26 and 27 are journaled in the framework of the carriage and are preferably provided with screwdown or adjustment means, indicated diagrammatically at 28.

The rolls 26 and 27 do not need to be continuous rolls extending transversely across the pack. They may instead comprise a series of two or more disc-like rolls, mounted upon common shafts.

Attached to a cross bar 29 on the carriage, we provide a forwardly extending framework 30 which moves with the carriage, as indicated in dotted lines in Figure 3, sliding on rollers 31, mounted upon brackets 32 on the main frame of the machine. The framework 30 receives one or more sheets as they pass between the pinch rolls 26 and 27 and ultimately delivers the separated sheets to the catcher hereinafter described.

A motor 33 is mounted upon the carriage framework and is operatively connected by a suitable drive to the pinch drive combination 26, 27 so as to drive these rolls.

For driving the carriage, an endless chain 34 is mounted along the frame 18 and passes over sprockets on shafts 35 and 36. A motor 37 or combination of motor and gear reducer is connected by a suitable drive, diagrammatically indicated at 38 to the shaft 36. The carriage 24 is, of course, affixed at one point to the endless chain 34. In order to assure uniform movement of the carriage, a chain 34 is preferably provided at each side of the frame.

The motor 37 is a reversible motor, and it will be understood that by driving the chain 34 in one direction or the other, it operates to cause a traverse of the carriage 24 both to the right and to the left in Figure 3. The motor 37 is provided with control circuits in such fashion that a complete traverse of the carriage will be effected automatically upon the actuation of a starting limit switch. A suitable wiring diagram for the motor is shown in Figure 7. A starting limit switch 39 is mounted upon the carriage in such a way as to be engaged by a sheet end introduced between pinch rolls 26 and 27. When this switch is thrown, the motor is started in operation in the forward direction, driving the carriage to the right, in the several figures. At the end of the traverse of the carriage in this direction, a bracket means 40 actuates another limit switch 41 which serves to reverse the motor 37, thus producing a traverse of the carriage in the opposite direction. When the carriage reaches the starting point, the same bracket, 40, actuates a third switch 42, which stops the motor. The circuits are such that when so stopped the motor is in circuit for the forward energization upon actuation of the switch 39. These various limit switches are arranged in appropriate circuits to energize the motor through appropriate relay or starting switches as shown. We also provide, in a position of convenient access to the operator, a series of switches, indicated at 43, for stopping the motor 37 and for producing forward and reverse movement thereof at will.

The operator's position will be at the left-hand end of the second section of the mechanism, illustrated in Figure 3, and various control means may be located there. These include a switch 44 (Figure 6) for the magnetic hold-downs 21, 22 which, of course, will be energized by direct current. The motor 33 for driving the pinch roll combination 26, 27 may be provided with a

circuit arrangement, as is also shown diagrammatically in Figure 7, and which includes a starting switch 45 and a stop switch 46. It is possible to make these switches in the form of limit switches actuated by the carriage at or near the limits of its traverse; but we find it more convenient to provide manual switches at the operator's station, since it is usually possible to keep the pinch roll combination 26, 27 in continuous operation during the whole of a stripping cycle, and it is also advantageous to give the operator separate control of the pinch roll combination.

At the same operator's station may be located mechanical or electrical valve control means for actuating the cylinders 13 and 16 described in connection with the first section of our apparatus.

A single operator is able to handle the first and second sections of our machine without difficulty, and as explained hereinafter, the action of the catcher and stacker may be made fully automatic so that no attendant operator at this point is required, unless inspection of a very close character is desired.

The pack opener operator positions the pack on table 2 and actuates a valve or switch for operating the clamp and guide combination. He then actuates another valve or switch for flexing the corner of the pack by means of the comb. Releasing the pack from the clamp, he then guides its travel along tables 2 and 19 until it is brought against the back-stop 20. He throws the switch 44 for energizing the magnetic hold-downs. With a tong he engages the topmost sheet of the pack and brings it upwardly (partially stripping it) until he can introduce its end between the driven pinch rolls 26 and 27. As the sheet end passes through these rolls, it trips limit switch 39, whereupon the carriage moves toward the right in the several figures, and a stripping operation occurs progressively and continuously. The carriage is stopped automatically at the right-hand end of its traverse, by means which have already been described, the sheet having now been completely stripped, and moving over the framework 30 under the influence of the pinch rolls. At the limit of the right-hand traverse of the carriage 24, the framework 30 substantially overlies the catcher mechanism next to be described; and since the traverse of the carriage from right to left begins immediately and automatically, the framework 30 is withdrawn from beneath the sheet.

As indicated in Figures 8 to 10 inclusive, the catcher comprises a suitable frame 47 upon which, at an elevated station underlying the framework 30, there are located a pair of drop plates 48 and 49 which are pivoted to the frame at their outer edges. The sheet 11a is delivered by the framework 30 onto these plates and comes to rest against an adjustable back-stop 50.

The plates 48 and 49 are pivoted by being attached respectively to shafts 51 and 52. These shafts are connected by suitable linkages 53 and 54 to an actuating device which may be an air cylinder 55 mounted upon an extension of the frame. This air cylinder may be controlled by a solenoid valve 56. As shown in Figure 6a, a switch 57 may be provided for this valve at the operator's station; but we also prefer to provide on the second section of our machine a limit switch 58. As shown in Figure 5, this limit switch is located upon the frame 18 of the second or stripper section in such a position as to be actuated by the bracket 40 on the carriage 24, when

the carriage attains starting position. By this means, the drop plates 48 and 49 are automatically actuated upon the completion of the carriage return.

The dropping of plates 48 and 49 by rotation of their shafts 51 and 52 results in depositing the sheet 11a upon a stack 53 resting upon a movable platform 60, which in turn may be supported upon transverse conveyor elements 61, so that the stack may be removed from the apparatus. A stationary end guide or abutment 62 is provided at one end of the stack, and at the other we provide an end guide or abutment 63, pivoted as at 64 to the movable abutment 60, and held in place by a link and rod arrangement 65 and 66, so that this abutment may be swung out of the way, as indicated in the dotted lines, when it is desired to remove the stack. At one side at least of the stack, we journal a shaft 67 connected by a linkage 68 to the shaft 51, and by this means to the air cylinder 55. To the shaft 67, we connect side abutment means 69, 70 by a linkage shown at 71 in Figure 10. Upon actuation the side abutment means 69, 70 move inwardly from the dotted line position in Figure 10 to the solid line position, thus enabling side alignment of the sheets in the stack. At the other side of the stack, we may provide a suitable removable abutment 72 or a fixed abutment which forms part of the platform 60.

As we have described above, the stripped sheets are delivered to the drop plates by means of the framework 30. The last sheet lying upon the conveyor table 19 is sent through the pinch rolls in the same fashion upon release of the magnetic hold-downs.

To assist in the positive removal of the various sheets from the framework 30, we provide on the end of the second section of our machine a pinch roll combination 75, 76 driven from a motor 75 through a gear reducer 76.

It is convenient to provide a means for throwing out defective or improperly stripped sheets. To this end, we mount on suitable brackets 77 above the frame 47, a shaft 78. Arm members 79 are affixed to this shaft. Other arm members 80 are pivoted to the ends of the first mentioned arms and a spring means 81 is employed to draw the arm members into alignment, as shown in dotted lines in Figure 11. The lowermost arm members carry means 82 to engage beneath the edges of sheets 11a lying upon the drop plates 48 and 49. The shaft 78 is connected by a link 83 to the piston 84 of an air cylinder 85 mounted upon the frame 47. This device constitutes a kicker, by means of which sheets 11a may be slid sidewise over the drop plates to be deposited alongside the catcher where waste receiving means may be positioned. A valve, or the switch for a solenoid valve (not shown), may be located in the operator's position. The operator, watching the stripping process, will thus be able to throw out any sheets which he sees are improperly stripped. If a closer inspection is desired, an inspector may be stationed at the catcher, in which event, the valve or switch for the air cylinder 85 will be located in a position of convenient access to him.

The operation of our apparatus will be clear from the description above. Instead of stripping a pack sheet by sheet, it has been found possible to strip a plurality of sheets from the pack and from each other simultaneously. This is accomplished by freeing the ends of a plurality of sheets in the pack and introducing them between

the pinch rolls 26, 27 in fanned or offset positions. The action of the apparatus remains the same; but as the sheets are drawn upwardly in the arc illustrated and passed through the pinch rolls, they are separated from each other because of their offset position, the separation occurring in the arc of movement prior to the passage of the sheets through the pinch rolls.

Modifications may be made in our invention without departing from the spirit thereof. Having thus described our invention, what we claim as new and desire to secure by Letters Patent is:

1. In a pack opening device, a bed upon which a pack may be placed, magnetic means for clamping the pack to the bed, a carriage movable above the bed parallel to the plane of the pack, pinch rolls mounted in said carriage between which the freed end of a pack sheet may be introduced, means for moving the carriage away from the end of the pack from which said sheet end has been freed and means for concurrently driving said pinch rolls, whereby the combined movement of the carriage and of the pinch rolls strips the partially freed sheet from said pack.

2. The structure claimed in claim 1 wherein a framework is attached to said carriage and extends forwardly in the direction of the last mentioned movement of the carriage to receive the stripped sheet.

3. The structure claimed in claim 1 wherein a framework is attached to said carriage and extends forwardly in the direction of the last mentioned movement of the carriage to receive the stripped sheet, and including a stacker mechanism to which said framework delivers said stacked sheet.

4. In a pack opening device, a frame, a bed mounted on said frame upon which a pack may be placed, means for clamping the pack to the bed, a carriage mounted on the frame above the bed and pack for movement longitudinally of the pack, pinch rolls mounted in the carriage, means for driving said pinch rolls, means for driving said carriage in a traverse path substantially throughout the length of said pack and back to a starting position, said pinch rolls being adapted to receive the freed end of a pack sheet, a limit switch located adjacent said pinch rolls to be contacted by a sheet engaged in said pinch rolls, said switch acting to initiate a traverse of said carriage away from the pack end from which said sheet has been freed, a second limit switch located beyond the opposite end of the pack to be actuated by said carriage to initiate return movement thereof, and a third limit switch located near the first mentioned end of said pack to stop the carriage upon completion of its return traverse.

5. The structure claimed in claim 4 including a framework attached to said carriage and extending forwardly in the direction of the forward movement of said carriage to receive a stripped sheet passing through said pinch rolls, and a stacker mechanism to which said framework delivers the stripped sheet.

6. The structure claimed in claim 4 including a framework attached to said carriage and extending forwardly in the direction of the forward movement of said carriage to receive a stripped sheet passing through said pinch rolls and a stacker mechanism to which said framework delivers the stripped sheet, said stacker mechanism comprising pivoted drop plates upon which said stripped sheet is deposited, means for

dropping said plates to deposit said sheet upon a stack, and means for actuating the dropping means including a control switch located to be actuated by said carriage upon completion of its return stroke.
